TRAVELING-WAVE TUBE ATTENUATORS

Kurt E. Zublin, Menlo Park, and Robert A. Craig, Palo Alto, Calif., assignors to General Electric Company, a corporation of New York

Filed Jan. 7, 1957, Ser. No. 632,841

13 Claims. (Cl. 315—3.5)

This invention relates to electron discharge devices and more particularly to improvements in high frequency electron discharge devices of the traveling-wave tube type.

Traveling-wave tubes may be employed in various applications and appear to be particularly suitable as amplifiers for high-frequency operation over a wide bandwidth. Some traveling-wave tubes employed as amplifiers include a translating element in elongated form adapted for propagating an electromagnetic wave therethrough. The translating elements are adapted by construction and arrangement to decrease the velocity of the electromagnetic wave along the axis of the translating element to a magnitude substantially less than the velocity of the waves in free space. The axial velocity of the electromagnetic wave is thus decreased to a velocity within the range of conveniently obtainable electron beam velocities. Such translating elements adapted for decreasing the axial velocity of an electromagnetic wave have been termed slow-wave structures. In the aforementioned amplifiers, input means may be provided for applying electromagnetic energy to one end of the slow-wave structure. Means may also be included for providing and directing an electron beam, which beam has a velocity approximately the axial velocity of the electromagnetic wave, and in energy-coupling relation with the slow-wave structure. Means may also be provided at the other end of the slow-wave structure for coupling out the amplified electromagnetic wave.

In such traveling-wave tube amplifiers, the useful gain which may be secured may be limited by unwanted reflections of electromagnetic waves by impedance mismatches between the slow-wave structure and the input or output coupler. The harmful effect of such mismatches, which heretofore have been unavoidable, are minimized, according to one feature of our invention, by incorporating in the slow-wave structure one or more attenuating sections which provide a very good electromagnetic match thereto. Such attenuators largely absorb rather than transmit or reflect the incident electromagnetic waves and therefore prevent successive energy reflections which degrade the performance of the amplifier and may in extreme cases lead to unwanted oscillation.

It is accordingly a principal object of the present invention to provide a traveling-wave tube adapted for high power level operation.

It is another object of the present invention to provide a novel attenuator device for use in connection with a slow-wave structure that is conducive to maintaining high efficiency of operation.

It is another object of the present invention to provide such a device in which the energy loss material is capable of dissipating relatively large amounts of heat, thereby providing short-circuited stable operation of the traveling-wave tube.

It is another object of the present invention to provide such a device in which the energy-loss material is concentrated in a relatively short length of a slow-wave structure.

2

It is another object of the present invention to provide such a device in which the energy-loss material or its resistivity may be tapered in a radial rather than axial direction.

5 It is another object of the present invention to provide such a device in which the performance is relatively insensitive to the resistivity or dimensions of the energy-loss material.

Further objects and advantages will become apparent 10 from the following description and the features of novelty which characterize the invention will be pointed out with particularity in the claims annexed to and forming part of the invention.

In the attainment of the foregoing objects, we provide 15 traveling-wave tubes including slow-wave structures consisting of periodic sections in seriatim. Attenuation members consisting of a relatively high-loss material concentrated in a relatively short length and having a cross-sectional area approximately equal to the area of cross-sections of the slow-wave structure are disposed in the slow-wave structures; one or more of said attenuation members interposed between predetermined ones of said periodic sections.

For a detailed explanation of our invention, reference 25 is made to the accompanying drawings in which like reference characters designate like elements throughout and in which:

Figure 1 is an axial cross-sectional view of a traveling-wave tube in accordance with the invention;

30 Figure 2 is an enlarged exploded view in perspective of the attenuator assembly of Figure 1;

Figure 3 is an enlarged axial cross-sectional view of the assembled attenuator of Figures 1 and 2;

35 Figure 4 is an axial cross-sectional view of another embodiment of the present invention;

Figure 5 is a fragmentary cross-sectional view of a portion of yet another embodiment of the present invention;

40 Figure 6 is an exploded view of another embodiment of attenuator assembly according to the present invention; and

Figure 7 is a longitudinal cross-sectional view of the assembled attenuator of Figure 6.

In Figure 1 there is illustrated a traveling-wave tube 11 in accordance with one embodiment of the present invention. Tube 11 includes an electron gun 15 consisting of a cathode 19; a cathode heater 21 connected to a suitable energizing source (not shown); a centrally apertured electron beam focusing electrode 23; and a centrally apertured electron beam accelerating anode 25. Electron gun 15 is located in a dielectric bulb 27 at one end of the tube 11, the left-hand end as oriented in the drawing, and provides an electron beam depicted by broken lines 53 which may be directed along the axis of the tube 11 as will be detailed hereinbelow.

55 An elongated slow-wave structure 29 is disposed between the electron gun 15 and a collector anode 31 located at the right-hand end of the tube 11. The slow-wave structure 29 may be a waveguide consisting of a series of spaced transverse conductive baffle plates 43 60 suitably affixed to a tubular conductor 45, the plates producing a structure in the nature of a loaded line to reduce the velocity of electromagnetic waves propagated therethrough to a value substantially below that in free space. Each of the plates 43 has a centrally located aperture 46 for permitting passage of the electron beam 53. An attenuator assembly 49, the details of which will be described hereinbelow, is disposed approximately midway between the ends of slow-wave structure 29. Collector anode 31 may consist of a capped tubular metallic member having an open end which may be joined to an output waveguide 51, and thence to the right-hand

end of the slow-wave structure 29. The bulb member 27, slow-wave structure 29, waveguide 51, and the collector 31 may be sealed in any suitable manner to provide an air-tight vacuum envelope. The collector 31 dissipates residual energy of the electrons and may be cooled, if necessary, in any suitable manner as, for example, by conduits 54 adapted to convey a cooling medium therethrough.

The electron beam 53 of predetermined desired velocity may be directed through the apertures 46 of plates 43 and in a path along the axis of the slow-wave structure 29. Focusing of the beam 53 throughout its travel along the slow-wave structure 29 axis may be obtained by a magnetic field directed along the axis of the structure 29. A solenoid 55 for producing such a field surrounds the tube 11 along its length in order to maintain a substantially constant axial field component. To simplify the drawing, the connection of the solenoid to a current source is not shown.

An electromagnetic wave may be coupled to the left-hand or cathode end of the slow-wave structure 29 by any suitable means known in the art and as shown, for example, by a coaxial line 57 having inner conductor 59 connected to the slow-wave structure 29 in such a way as to form either probe or loop coupling to the first section thereof, and outer conductor 61 connected to ground reference. Output coupling means consisting of any type known in the art suitable for high-power level operation such as, for example, the waveguide structure 51 having a coupling probe 65 inserted in the broad wall of the waveguide is provided at the opposite or collector end of the slow-wave structure 29 to couple the output from the traveling-wave tube 11 to a utilization circuit, not shown.

A power source 67 having a positive terminal connected to the anode 31 and also to ground reference and a negative terminal connected, as shown, to the electrode 23 provides direct-current operating potential. Cathode 19 may also be connected to the negative terminal of source 67. Accelerating anode 25 may be connected to an adjustable tap 69 of source 67 for the purpose of obtaining a more positive potential than is applied to cathode 19.

As seen in Figures 1, 2 and 3, attenuator assembly 49 may include a pair of disks 71 and 73 which may be identical to one another and formed of lossy or energy-dissipating material such as, for example, carbonized porous ceramics, lossy ferrites or any such lossy materials which have the property that the amount of loss introduced thereby can be controlled. Furthermore, the material is desirably one which is relatively stable with temperature.

We have found that materials of which the resistivity is of the order of one thousand times that of carbon give suitable loss and have the desirable property that the wave-absorbing property is relatively insensitive to the resistivity or tolerance dimensions of the energy-dissipating body.

A suitable attenuator disk construction that we have found to operate satisfactorily is fabricated from a disk of porous alumina that has been preliminarily soaked, at room temperature, for a few hours in an aqueous sugar solution. The concentration of the solution can range from approximately 10% to 50% according to the desired resistivity. After drying in hot air at any convenient temperature below 200 degrees centigrade, the body is thereafter fired for about 10 minutes in a neutral atmosphere at about 1000 degrees C. We have found that firing in a hydrogen furnace produces a desirable product. The dryness of the hydrogen is relatively important since a very small amount of oxygen is sufficient to burn off carbon. The firing operation transforms the sugar into carbon having the aforementioned desirable loss characteristic that is relatively insensitive to resistivity or tolerance dimensions of the attenuator body.

Disks 71 and 73 are located at a predetermined point

along the length of the slow-wave structure 29 and desirably near the center of the slow-wave structure. The cross-sectional area of disks 71 and 73 of the attenuator 49 is effectively equal to or corresponds to the cross-sectional area of the slow-wave structure 29, although employment of bodies fabricated as above-described yields considerable freedom as to dimensional tolerances.

The individual elements of attenuator 49 are shown in the exploded view of Figure 2. A centrally apertured 10 circular conductive plate 75 has an outstanding flange or drift tube 77 in the region of the central aperture and is disposed between the disks 71 and 73. Plate 75 includes ledges or rings 79 and 81 having an inner diameter approximately equal to the outer diameter of the 15 disks 71 and 73 to provide snug fit therefore. Plate 75 provides radio-frequency isolation between the input and output ends of the slow-wave structure 29. The plate 75 provides the additional action of cooling the attenuator discs 71 and 73. This cooling action is sufficient for most 20 applications. However, it has been found that the thickness of the plate 75 can be varied without deleterious effects on tube performance, consequently, cooling ducts (not shown) may be provided inside this plate and a cooling fluid circulated therein. With such an arrangement, the attenuator discs 71 and 73 are cooled to a 25 temperature dependent upon the radio frequency power absorbed in the attenuator, the rate of fluid flow, and the fluid temperature as well as the particular geometry of the combination of plate 75 and discs 71 and 73. 30 When assembled, the drift tube 77 extends along the inner rim of the disks 71 and 73 and shields the disks from impingement by the electron beam 53. Two slotted metallic conducting coupling pieces 83 and 85 have respective sets of raised ledges or rings 87, 89 and 91, 93 35 to snugly receive and support the disk members 71 and 73, respectively. Coupling pieces 83 and 85 have respective outer flanges 95 and 97 which may be adapted to bear against rim 82 of plate 75. Coupling pieces 83 and 40 85 provide additional radio-frequency matching network necessary in some cases to eliminate reflections from the attenuating disks. This type construction provides a compact assembly which may occupy in the tube approximately the same longitudinal length as but one section 45 of the slow-wave structure 29.

If desired, or where required to improve continuity of transition between the attenuator sections and the next adjacent slow-wave section, the disks 71 and 73 may be actually or effectively tapered in a radial direction relative the axis of the tube. Thus, instead of being of 50 uniform axial thickness, as shown, the disks may be of non-uniform thickness, as, for example, by having a maximum thickness at the peripheral region and a relatively fine or thin inner edge. Also, and depending on the observed mode of excitation of the adjacent sections, the 55 disks may be tapered with a minimal thickness near the peripheral edge and maximal thickness at the center. The taper can be employed with linear variation of thickness or other relations such as

$$60 \quad \frac{1}{r^2}, \frac{1}{r^3}$$

where r is the radius of the disk, according to the desired smoothness of electrical continuity sought to be accomplished. It will be understood that in lieu of geometrical tapering as just described, a tapering effect can be accomplished as by selectively and radially controlling the density or amount of lossy material embedded within uniform-thickness ceramic or other porous base.

The slow-wave structure 29 consists of an input portion 42 separate, and in axial alignment with, an output portion 44. In operation of tube 11, an electromagnetic wave is coupled by coaxial line 57 to the input portion 42 of the slow-wave structure 29 and is propagated along the slow-wave structure 29 and serves to modulate the electron beam 53 being directed through

the slow-wave structure. The electromagnetic wave is completely absorbed, for all practical purposes, in the lossy disk terminating member 71. The electron beam 53 which has been modulated by the input electromagnetic wave passes through the aperture 77 in attenuator 49. The electron beam 53 generates high frequency energy in the output portion 44 of the slow-wave structure 29 in accordance with the input modulation. The amplified output energy is coupled to the waveguide 51 by the coupling probe 65.

Since the attenuator assembly 49 may be constructed to provide almost complete absorption or decoupling of the electromagnetic wave, the input and output portions of the traveling-wave tube may be made to serve entirely different functions such as, for example, would be required in a generator of harmonic components of the fundamental electromagnetic wave introduced into the input end 42 of the slow-wave structure. In such a case, the output portion could be designed to amplify a harmonic of the frequency of the input portion. The input portion 42 may conceivably be constructed as a tunable oscillator and the output portion may be adapted to amplify the oscillation frequency or a harmonic thereof.

Figure 4 shows a slow-wave structure 99 employed in a traveling-wave tube of a similar type to a slow-wave structure 29 of Figure 1 and in which a plurality of slow-wave structure portions or stages, isolated electrically from one another by attenuators, provide high power gains while eliminating any tendency toward undesired oscillations. The slow-wave structure 99 includes three operating stages 101, 103 and 105 which are isolated electrically from one another by attenuator assemblies 107 and 109, each of which attenuators may be similar to attenuator assembly 49 of Figure 1. An electron beam 53 is modulated by an electromagnetic wave coupled to the input portion 101 of slow-wave structure 99 from an input coaxial line 57. An attenuator disk 111 on the input line side of the attenuator 107 absorbs the electromagnetic wave, but allows the modulated beam to proceed to the next portion 103 where the beam energizes an augmented electromagnetic wave therein in accordance with the input modulation. An attenuator disk 113 on the output side of the attenuator 107 absorbs any reflected waves to prevent undesired oscillations in that section of the tube. This operation of energizing an augmented wave is repeated in output portion 105, and as many times thereafter as desired to obtain the desired power gain in the amplifier. The output energy may be coupled out through probe 65 inserted in a waveguide 51.

Another embodiment of the attenuator construction according to the present invention is shown in Figure 5. An attenuator 121 includes a single lossy disk 123 apertured to accommodate an electron beam 53 which attenuator is inserted in the slow-wave structure 29 to provide attenuation. The slow-wave structure 29 and electron beam 53 may be similar to that of Figure 1. Slotted baffle plates 125 and 127 disposed on either side of the disk 123 may be constructed, each having an inner ring support ledge 129 and 131 and an outer ring support ledge 133 and 135, respectively, to provide support for the disk member 123. The attenuator 133 is substantially reflectionless and can be made of such dimensions and material that a predetermined fraction of incident electromagnetic energy can be attenuated or absorbed thereby. Varying degrees of attenuation can be obtained with the embodiment of Figure 5 as compared to almost complete absorption of the input electromagnetic wave desired to be provided by the attenuator of Figures 1-4. In one type of operation of a traveling-wave tube employing the attenuator as shown in Figure 5 and having other elements otherwise similar to those of Figure 1, an electromagnetic wave is coupled to one end, not shown, of the slow-wave structure 29 and transmitted directly through the slow-wave structure. The introduced electromagnetic wave is in continuous en-

ergy interacting relation with the electron beam 53 throughout the length of the slow-wave structure 29. The augmented electromagnetic wave is extracted from the opposite end, not shown, thereof. The attenuator 133 can be made with just sufficient loss to prevent undesired oscillations such as those caused by amplification of the backward traveling-wave or those caused by reflections from the impedance mismatch.

Figures 6 and 7 show still another embodiment of an attenuator assembly 137 according to the present invention. An attenuator assembly includes two lossy disk members 139 and 141 which may be fabricated as above-described in connection with disks 71 and 73. A centrally apertured flat conductive plate 143 having an outstanding flange or drift tube 145 in the region of the central aperture is disposed between disks 139 and 141. Two radially slotted metallic side pieces 147 and 149, each having an outer rim flange 151 and 153, respectively, enclose the attenuating disks 139 and 141. Each of the side pieces 147 and 149 include a plurality of wedge-shaped conductive members 155 extending radially inwardly from the rim flanges 151 and 153 and are quadrantly disposed between adjacent pairs of slots, as shown. The side pieces 147 and 149, the wedge-shaped metallic members 155 and the spaces 156 between the members 155 which separate the side pieces from the attenuating disks 139 and 141 cooperate to define an impedance matching network which we have found useful to eliminate reflections from the disks. A fuller description of the so-called "clover-leaf" structure of the aforescribed type is given in a publication by one of us, Robert A. Craig, entitled, "Study of Periodic Structures for High Voltage Traveling-Wave Tube Operation," Technical Report #36, dated November 2, 1954, and published by Stanford University.

The attenuator assembly is shown as assembled in a portion of a slow-wave structure 157, Figure 7. Slow-wave structure 157 may be of the "clover-leaf" structure.

As shown in Figure 7, the drift tube 145 may extend along the inner rim of the disks 139 and 141 to provide radio-frequency isolation between the input and output sections 159 and 161 of the slow-wave structure 157 as well as partially to shield the disk from possible impingement by the electron beam. The length of the drift tube 145 may be selected to control the amount of decoupling between the two sections 159 and 161 and contributes in some cases to the impedance match. The operation of the just-described attenuator assembly in slow-wave structure 157 is generally similar to the operation of attenuator assembly 49 in slow-wave structure 29 described above in relation to Figure 1.

While specific examples have been given describing details of this invention, it will be understood that they are given merely by way of illustration and that the invention is to be construed as including other modifications within the true spirit and scope of the appended claims.

What we claim as new and desire to obtain by Letters Patent of the United States is:

1. An electron discharge device of the traveling-wave type comprising means for providing an electron beam, an elongated slow-wave structure, said slow-wave structure comprising a waveguide having a plurality of spaced transverse plates, each of said plates having a substantially centrally located aperture therethrough, input and output means connected at opposite ends of said slow-wave structure, an attenuation section interposed approximately at the center of said slow-wave structure, said attenuation section including a disk-shaped body of relatively high loss material having approximately the same cross-section as said transverse plates, and centrally apertured impedance matching means disposed on opposite sides of said body of high loss material, said attenuation section being positioned in substantial alignment with said transverse plates whereby a continuous path is pro-

vided through said plates and said attenuation section to permit passage of said electron beam.

2. In an electron discharge device of the traveling-wave type a slow-wave structure comprising a loaded waveguide, said waveguide comprising a tubular member, a plurality of extending spaced parallel transverse plates affixed to said tubular member, an attenuation section disposed at a predetermined point in said slow-wave structure, said attenuation section comprising at least one attenuation member and impedance matching means on opposite sides of said attenuation member, each said attenuation member being disk-shaped and having approximately the same cross-section as said slow-wave structure said attenuation section and each of said plates having a substantially centrally located aperture therethrough.

3. In an electron discharge device of the traveling-wave type, a slow-wave structure comprising a plurality of periodic sections capable of propagating an electromagnetic wave therethrough, an attenuation section in said slow-wave structure comprising a first disk member, a second disk member, said disk members comprising lossy material and each having a cross-section approximately the same as the cross-section of said slow-wave structure, a first conductive plate interposed between and in contiguous relation with said disk members, said disk members disposed at a point along the length of said slow-wave structure to provide attenuation, and a pair of conductive plate members disposed on opposite sides of said disk members adapted to couple said wave to said disk member said first and second disk members, said conductive plate and said pair of conductive plate members each having centrally located apertures therethrough for accommodating the passage of an electron beam.

4. In an electron discharge device of the traveling-wave type, a slow-wave structure comprising a plurality of periodic sections capable of propagating an electromagnetic wave therethrough, an attenuation section in said slow-wave structure comprising a single disk member, said plurality of periodic sections and said attenuation section having apertures therethrough to permit passage of an electron beam, said disk member comprising a lossy material having a cross-section approximately the same as the cross-section of said slow-wave structure, and means including a pair of conductive plate members disposed on opposite sides of said disk members and adapted to couple said wave to said disk member.

5. In an electron discharge device of a traveling-wave type having a slow-wave structure in the form of a loaded waveguide having a plurality of periodic sections capable of propagating an electromagnetic wave therethrough, an attenuation section having substantially the same cross-section as said periodic sections and comprising at least one disk member containing lossy material, and matching means on opposite sides of said section for coupling said wave to said disk member, said attenuation section having a centrally located aperture therethrough disposed in said slow-wave structure between respective ones of said periodic sections.

6. In an electron discharge device, a slow-wave structure comprising a plurality of interacting portions in axial alignment and capable of propagating an electromagnetic wave therethrough, attenuation sections of substantially the same cross-section as said interacting portions for terminating respective portions of said slow-wave structure, and at least one of said attenuation sections interposed between adjacent interacting portions, the said attenuation sections including at least one centrally apertured disk-shaped member of substantially the same cross-section as said interacting portions and at least a pair of centrally apertured impedance matching members disposed on opposite sides of said attenuation sections whereby said attenuation sections are capable of dissipating large amounts of electromagnetic power for obtaining stable operation of said device in conjunction with a wide variety of load mismatches.

7. In an electron discharge device, a slow-wave structure comprising a plurality of periodic sections capable of propagating an electromagnetic wave therethrough, at least one attenuation section of substantially the same cross-section as said interacting portions for terminating predetermined sections of said slow-wave structure, at least one disk member containing lossy material in each said attenuating section, and impedance matching means on opposite sides of said attenuation section for coupling electromagnetic waves to said disk member, said attenuation section having a centrally located aperture therein to accommodate passage of an electron beam and being inserted in said slow-wave structure separating respective ones of said periodic sections, the said attenuation sections being capable of dissipating relatively large amounts of electromagnetic power for obtaining stable operation of said wave structure in said device.

8. In an electron discharge device of the traveling-wave type having a slow-wave structure comprising a loaded waveguide, said waveguide including an outer tubular member and a plurality of inwardly extending spaced parallel transverse plates, said plates being joined to said tubular members and defining a central aperture for accommodating an electron beam, an attenuation section adapted for insertion at a predetermined point in said slow-wave structure, said attenuation section comprising at least one attenuation member having a cross-section approximately equal to that of the slow-wave structure, said attenuation member having an axial dimension comparable with that of one section of said slow-wave structure, and support means for said attenuation member, said support means comprising a pair of conductive plates each having radial slots coupling wave energy to said attenuation member and flange means to support said attenuation member in predetermined fixed position in the tubular member said conductive plates and said attenuation member having centrally located apertures therethrough in substantial alignment with the said central aperture defined by said spaced parallel transverse plates to permit the passage of the electron beam.

9. An electron discharge device of the traveling-wave type comprising a periodic slow-wave structure capable of propagating an electromagnetic wave therethrough, means producing an electron stream in energy interacting relation with said slow-wave structure, means coupling electromagnetic wave energy to one end of said slow-wave structure, said slow-wave structure comprising an elongated body portion of relatively low attenuation, at least one section of relatively high attenuation interposed at a predetermined point along the length of said relatively low attenuation body portion, said high attenuation section being of approximately the same cross-sectional area as said body portion and including a centrally apertured disk-shaped member of lossy material and centrally apertured impedance matching means on opposite sides of said disk-shaped member, the axial extension of said high attenuation section being in approximately the same order of magnitude as the spacing between periodic portions of said slow-wave structures, and means coupled to the opposite end of said slow-wave structure for deriving energy therefrom.

10. An electron discharge device of the traveling-wave type comprising a periodic slow-wave structure capable of propagating an electromagnetic wave therethrough, means producing an electron stream in energy interacting relation with said slow-wave structure, means coupling electromagnetic wave energy to one end of said slow-wave structure, said slow-wave structure comprising a plurality of elongated body portions of relatively low attenuation and having centrally located apertures therethrough defining a path for electron stream, sections of relatively high attenuation interposed between said low attenuation sections, said high attenuation section being of approximately the same cross-sectional area as said body portions of relatively low attenuation, said sections

of relatively high attenuation including impedance matching means for matching electromagnetic waves propagating through the periodic slow-wave structure to said high attenuation section and means coupled to the opposite end of said slow-wave structure for deriving energy therefrom.

11. In an electron discharge device of a traveling-wave type comprising a nearly periodic slow-wave structure through which an electromagnetic wave is propagated, said slow-wave structure comprising a plurality of sections of relatively low attenuation, and a section of relatively high attenuation interposed at a point along the length of said low attenuation section, said high attenuation section comprising a generally disk-shaped material having substantially the same cross-section as the cross-section of said slow-wave structure and having loss properties or dimensions which are tapered in a radial direction to provide high attenuation for traveling electromagnetic waves, impedance matching means on opposite sides of said disk-shaped material, said high attenuation section having a centrally located aperture there-through.

12. In an electron discharge device of a traveling-wave type comprising a nearly periodic slow-wave structure through which an electromagnetic wave is propagated, said slow-wave structure comprising sections of relatively low attenuation, a section of relatively high attenuation interposed at a point along the length of said low attenuation section, said section of relatively high attenuation having substantially the same cross-section as said low attenuation section and including a centrally apertured generally disk-shaped member of lossy material having

substantially the same cross-section as said section of relatively high attenuation and centrally apertured impedance matching means on opposite sides of said disk-shaped member, the performance of said high attenuation section being relatively insensitive to the loss properties or dimensions of the energy loss material.

13. In an electron discharge device of a traveling-wave type comprising a nearly periodic slow-wave structure through which an electromagnetic wave is propagated, 10 said slow-wave structure comprising sections of relatively low attenuation, a section of relatively high attenuation interposed at a point along the length of said low attenuation section, said section of relatively high attenuation including a material having a resistivity of the order of one thousand times that of carbon and a cross-section substantially the same as said section of relatively high attenuation and impedance matching means for matching said relatively high attenuation section to said low attenuation slow-wave structure.
